PAPER FEEDING MECHANISM

Raymond G. Bower, Detroit, Mich., assignor to
 Burroughs Adding Machine Company, Detroit,
 Mich., a corporation of Michigan

Application December 9, 1933, Serial No. 701,616

9 Claims. (Cl. 197—138)

This invention relates to paper feeding mechanism for typewriters, calculating machines and the like, particularly to the feed roll and paper pan features of such machines.

5 The general object of the invention is to provide improved paper feeding mechanism for typewriters, calculating machines and the like.

A more particular object is to provide improved feed roll mounting and feed roll releasing means 10 for such machines.

A further object is to provide an improved paper pan arrangement and mounting for such machines.

Still another object is to provide improved 15 means for automatically closing the gap between the feed roll and the paper pan when the feed roll and platen are separated.

Other and more particular objects will herein-after appear.

20 An embodiment of the invention is shown in the accompanying drawings, in which:

Figure 1 is a perspective view of the invention with some of the parts spread to illustrate them more clearly;

25 Fig. 2 is a sectional elevation of the invention with the feed rolls in engagement with the platen;

Fig. 3 is a view similar to Fig. 2 with the feed rolls out of contact with the platen; and

30 Fig. 4 is a detail view of a portion of the feed roll releasing means.

The invention is shown applied to the traveling paper carriage of a typewriter, which carriage comprises side plates 10 and 11 joined by a cross piece 12 and a back plate 13. A rotatable platen 35 P is suitably journaled in the cross plates 10 and 11.

Feed roll mounting

Associated with the platen P are front and rear 40 feed rolls adapted to cooperate with the platen to hold papers thereagainst and to cause the papers to be line spaced or fed as the platen is rotated.

The front feed rolls 20 are carried by a shaft 21 supported on arms 22 pivoted on a shaft 23 45 that is fixed in end plates 24, shown in Fig. 1, said end plates being fixed to the carriage rail 12. The arms 22 have downwardly extending L-shaped arms 25 (Fig. 1), and, connected between the ends of these arms and studs 26 on the stationary brackets 24, are springs 27 whose tension is adjustable by means of screws 28. These 50 springs exert a tension on the arms 22 tending to urge them counterclockwise about their pivots 23 (Fig. 2) so that the front rolls 20 are urged toward the platen P.

A single rear feed roll 30 is shown in the present embodiment, but several rear feed rolls may be used if desired. The rear roll 30 is carried by a shaft 31 journaled in arms 32 pivoted on the shaft 23. These arms are urged clockwise about their pivots 23 by springs 33 connected to the arms and to brackets 34 on the back plate 13. The tension of springs 33 may be adjusted by means of screws 35.

From the description given, it will be clear that 10 the front and the rear feed rolls are urged toward the platen by separate spring means so that the tension of the rolls may be varied independently. This enables the tightness with which the rear roll grips the paper to be varied 15 with respect to the tightness with which the front rolls grip the paper and it has been found that this enables a better feeding action to be obtained.

Feed roll release means

20

The feed rolls may be moved out of engagement with the platen and held in this position while a paper or papers are being passed about the platen after which the feed rolls can be released for engagement with the papers to hold 25 them in feeding relation to the platen.

The feed rolls are released by means of a feed roll release lever 40 having a thumb piece 41, said lever being journaled on a shaft 42. The lower end of the lever has a toothed sector 43 whose teeth mesh with teeth on a sector 44 fixed to a feed roll release shaft 45 journaled at one end in the end plate 11 and at its other end in the left hand bracket 24 fastened to the cross plate 12.

The release shaft 45 has a plurality of notches 46 and 47 in it corresponding in number to the number of levers 22 and 32 which carry the front and rear feed rolls respectively. These notches are shown in Fig. 4 where it will be seen that there is a separate notch for the rear and front feed roll carrying levers, the notches 46 being for the front feed roll levers and the notches 47 for the rear feed roll levers. These notches form actuating cam surfaces for the feed roll levers and the periphery of the shaft 45 forms a "dwell" portion of the cams.

The front feed roll supporting levers 22 have downwardly projecting arms 50 provided with surfaces 51 adapted to engage in the slots 46 of 50 shaft 45.

The lower ends of the rear feed roll supporting levers 32 have cam ends 52 adapted to engage in the slots 47.

When the feed rolls are in engagement with 55

the platen, the parts occupy the position illustrated in Fig. 2 where the cam edges 51 and 52 are in the slots 46 and 47, respectively.

When the feed roll release lever 40 is pulled 5 from the position of Fig. 2 to that of Fig. 3, the shaft 45 is turned to the position of Fig. 3 where, it is to be noted, the cam edges 51 and 52 of the levers 22 and 32 are not only out of the slots 46 and 47, but a considerable portion of the periphery of the shaft 45 is turned under the ends or edges of these levers. Two functions are accomplished by this construction and arrangement of parts, with the following advantages.

In the first place, the feed roll release shaft 15 45 is relieved of torsional strain when the feed rolls are in released position because, at that time, the edges 51 and 52 are bearing against the periphery of the shaft 45 without exerting any tendency to turn it.

20 The second function and advantage is that it is not necessary to provide a detent to hold the feed roll release lever in its released position. In constructions in which the active cam surfaces remain in engagement with the feed roll supporting levers, some sort of detent has to be provided to hold the levers out of engagement with the platen. But, with the construction above described, not only is the release shaft relieved of torsional strain, but the feed roll release lever 25 need not be provided with a detent.

Paper pan mounting

Positioned beneath the platen is a paper pan 35 60 mounted so that it is fully "floating", that is, it is not moved to and from the platen at the time the feed rolls and platen are separated.

This pan is in the form of an arcuate metal sheet adapted to fit the under surface of the platen. Toward its forward edge, the pan is 40 provided with downwardly extending lugs or projections 61 having L-shaped slots 62 in them by means of which the projections may be fitted over the shaft 21 which acts as a guide for the pan. Near its rear edge the pan may rest 45 on the arms 32 although it does not normally rest on such arms owing to the fact that the pan is urged toward the platen by springs 63 near both ends, said springs surrounding a shaft 23 in each of the two brackets 24 and each having 50 one of its ends bearing against the underside of the pan 60 and the other end bearing against the shaft 45. The springs cause the pan to lightly engage the platen, the pan being free of the feed rolls and not being disturbed by movement of these rolls into and out of engagement 55 with the platen. The rear end of the pan is limited in its upward movement by engagement with the back plate 13, as shown in Fig. 2, so that there is always a slight space between the 60 pan and the platen for the reception of a paper or papers that may be inserted.

The front or forward portion of the pan is urged into engagement with the platen at all 65 times by the springs 63. This engagement is light so that it does not interfere with the progress of paper that may be inserted from the rear but is heavy enough to lightly hold the paper after it has been inserted.

When the feed rolls 20 and 39 are moved away 70 from the platen, the paper pan remains in the same position as it did while the rolls were engaging the platen, as will be clear from the illustration of the parts in Figs. 2 and 3. When the feed rolls have been released, a paper may 75 be inserted from the rear and this paper will be

held in contact with the platen by the relatively light urge of the front edge of the paper pan. The paper is thus held while the feed rolls are moved toward the platen, with the result that the papers are gripped accurately instead of being moved as they might be if the paper pan moved to and from the platen.

Another advantage of the construction is that considerable friction between the paper pan and the platen is removed so that the papers can 10 slide forward easily. If the pan were to grip the platen over its entire lower surface, a snubbing action would result and the paper would have a tendency to cling or stick to the platen which would make it hard to move to position.

If the platen is removed from the carriage for any reason, the paper pan 60 remains in position even though it is urged upward by the spring 63. This is due to the fact that the slots 62 in the projections 61 are L-shaped and the bottom of the slots catch on the shaft 21 and the back plate 13 block the rear end of the pan 60. This enables the platen to be removed and reinserted without requiring the operator to rearrange or adjust the springs that urge the pan upward. At the same time, the pan can be removed if desired by moving it forward slightly while the horizontal portions of the slots 62 are in position to permit projections 61 to slip off shaft 21.

Means for automatically closing the gap between the feed roll and the paper pan when the feed roll and platen are separated

As shown in Figs. 1 and 2, the rear feed roll 30 is adapted to engage the platen through a slot or opening 70 in the paper pan. It is necessary to have the feed roll spaced a substantial distance from the edge of this opening in order that the feed roll may rotate freely while it is in engagement with the platen. When this is done an opening or gap 71 exists between the feed roll and the edge of the opening in the pan.

This gap has been considered a necessary evil in many paper feeding constructions. The difficulty with the gap is that there is a tendency for papers, particularly if they are stiff, to catch in the gap when they are being fed under the platen from the rear. This is particularly true in a construction where the paper pan is full floating, that is, where it does not move away from the platen at the time the feed rolls are moved away. For example, referring to Fig. 2, it will be clear that if the rear feed roll 30 is moved downward from its Fig. 2 position, the gap between it and the edge of the opening in the pan will tend to become larger and more susceptible to stopping papers.

To avoid the difficulty, means has been provided for automatically closing this opening or gap when the rear feed and platen are separated. In the embodiment shown, this consists in mounting the rear feed roll shaft in inclined slots 80 in the arms 32. As the feed roll is moved away from the platen, the weight of the roll is enough to cause it to move downward and forward in the slots 80 from the position of Fig. 2 to that of Fig. 3 where it will be observed that the feed roll closes 70 the gap so that the papers cannot catch in the opening.

As the feed rolls are moved away from the platen the feed roll shaft 31 moves behind shoulders 81 on the brackets 24 (Figs. 3 and 1) which 75

prevent the feed rolls being pushed up in the slots 80 when a stiff card is inserted.

When the feed roll is moved toward the platen again, the influence of the springs 33 is such as 5 to cause the rolls to roll upwardly so that the supporting shaft 31 moves from the position of Fig. 3 to that of Fig. 2 where the feed roll is free to rotate without interference from the pan. This movement of the feed roll also tends to smooth 10 out the papers which are held by the front edge of the paper pan and the front feed rolls.

While the above construction has been shown with only a single rear feed roll, it will be clear 15 that the same construction could be used with a plurality of rear rolls or with front rolls if such construction were designed for a set of front rolls. Likewise, while, in the embodiment illustrated, the feed roll is moved away from the platen to provide a throat or opening for receipt 20 of papers, the construction would operate if the platen were moved away from the feed roll to provide this opening.

It will be understood that the construction shown is for purposes of illustration only and 25 that variations may be made in it without departing from the spirit and scope of the invention as defined by the appended claims.

I claim:

1. In a machine of the class described, a platen, 30 front and rear feed rolls movable into and out of engagement with said platen, means supporting said rolls, a paper pan guidingly interlocked with said roll supporting means and mounted so as not to be affected by the movement of said rolls into 35 and out of engagement with said platen, means for urging said pan into engagement with said platen, and means for limiting the movement of the rear portion of said pan toward said platen whereby a slight space remains between said 40 platen and the rear of said pan while the front edge of said pan engages said platen whereby papers may be easily fed under said platen from the rear but will be lightly gripped at the front of said platen.

2. In a machine of the class described, a platen, 45 feed rolls movable into and out of engagement with said platen, a paper pan mounted so as not to be affected by the movement of said rolls into and out of engagement with said platen, means urging said pan upward toward said platen, and means operable to limit the upward movement 50 of said pan when said platen is removed, said means being also operable to enable the pan to be quickly removed when desired.

3. In a machine of the class described, a platen, 55 a paper pan cooperating with said platen, a feed roll adapted to engage said platen through openings in said paper pan whereby a gap is left between said roll and said pan, means for separating said feed roll and said platen, and means automatically closing the gap between said feed roll and pan as said feed roll and platen are separated.

4. In a machine of the class described, a platen, 60 a paper pan cooperating with said platen, a feed roll adapted to engage said platen through open-

ings in said paper pan whereby a gap is left between said roll and said pan, means for separating said feed roll and said platen, means automatically closing the gap between said feed roll and pan as said feed roll and platen are separated, and means for holding said gap-closing means in gap-closing position while said feed rolls and platen are separated. 5

5. In a machine of the class described, a platen, 10 a paper pan cooperating with said platen, a feed roll adapted to engage said platen through an opening in said paper pan so that a gap remains between said roll and said pan, means for separating said feed roll and said platen without moving said paper pan whereby the tendency is for 15 said gap to become more effective in catching papers that may be inserted between said feed roll and platen, and means automatically closing said gap as said feed roll and platen are separated. 20

6. In a machine of the class described, a platen, 25 a paper pan cooperating with said platen, a feed roll adapted to engage said platen through an opening in said paper pan so that a gap exists between said roll and pan, means for separating 30 said feed roll and platen, and supporting means for said feed roll operable, as said roll and platen are separated, to cause said roll to automatically close said gap.

7. In a machine of the class described, a platen, 35 a paper pan cooperating with said platen, a feed roll adapted to engage said platen through an opening in said pan so that a gap is formed between said roll and pan, means for separating said feed roll and platen, and arms carrying said feed roll having inclined slots in which said feed roll is mounted, so that, as said feed roll and platen are separated, said feed roll will move in 40 said inclined slots to close said gap.

8. In a machine of the class described, a platen, 45 a paper pan cooperating with said platen, a feed roll adapted to engage said platen through an opening in said pan so that a gap is formed between said roll and pan, means for separating said feed roll and platen, arms carrying said 50 feed roll having inclined slots in which said feed roll is mounted, so that, as said feed roll and platen are separated, said feed roll will move in said inclined slots to close said gap, and means for holding said roll in gap closing position while said roll and platen are separated.

9. In a machine of the class described, a platen, 55 a floating paper pan urged into engagement with said platen so as to loosely engage said platen at the front and to be slightly spaced therefrom at the rear, whereby papers may be easily inserted under said platen from the rear and will be loosely held at the front, front and rear feed rolls adapted to be moved into and out of engagement with said platen, and means for causing 60 said rear feed roll, as it engages said platen at the rear, to move upward slightly while the paper is held at the front by said paper pan and said front feed rolls. 65

RAYMOND G. BOWER. 65
